UNITED STATES PATENT OFFICE.

ALBERT C. FISCHER, OF CHICAGO, ILLINOIS.

RAIL FILLER.

Application filed August 30, 1926, Serial No. 132,545. Renewed May 9, 1927.

My invention relates in general to paving and other construction projects in which tracks or rails for street railways are imbedded in paving and other places, and has particular reference to means to be used in combination with the rails for sound deadening purposes, for absorbing vibrations of shock, for compensating for expansion and contraction of the structure in which the rails are imbedded, and for otherwise improving the installation and maintenance of tracks and adjoining paving structures.

Briefly, my invention has to do with a so-called preformed rail filler, its fabrication and application to the rail being well illustrated in the accompanying drawing, in which Figure 1 is a perspective view of a rail section illustrating the filler proposed by the present invention applied to both sides thereof.

Figure 2 is a detailed perspective view of a section of the rail filler; and

Figure 3 is a perspective view of a section of rail of the flange type illustrating the application of the filler to one side thereof.

Referring now to the drawing in detail. Ordinary or conventional types of track rails have a head A, base B, connecting web C, with a space between the head and base. It so happens when a rail, for instance in city streets, is imbedded in the paving structure the paving material usually intimately contacting with the rail, filling in the space between the head and base, consequently leaving no chance for the sound of the cars passing over the track to be muffled or deadened, then again expansion and contraction not being provided for is apt to crack the pavement.

According to my invention instead of permitting the paving structure in which the rail is imbedded to contact with the paving material, I propose to fill the space on one or both sides of the web C with material suitable for the purpose, which for the most part will be some readily compressible material, such as, asphalt mixed with fibrous material, such as, felt, sawdust, corn cob fibre, roofing scrap, or the like, the idea being to make up a soundproof, preformed, blocklike strip, extruded or otherwise molded to fit the space between the head A and base B, as best shown in Figures 1 and 3.

In this particular case I am not so much concerned with the composition of the material, nor the way it is fabricated, nor the

preformed shape or dimension of the same, the present case having to do more with the means for anchoring the material with the rail so as to prevent dislocation. For this reason I will not go into details concerning the construction of the material, so that it may be considered any block-like piece or member made of any shape suitable for the purpose and of any desired composition.

The invention primarily comprises a combination between a rail provided with means to interlock with means on the filler for anchoring the filler to the rail. In this connection I suggest that the rail be constructed with projections projecting into the space to be filled by the filler from either the head, web or base thereof.

So far as the illustration in the accompanying drawing is concerned the underside of the head A is made with a projecting tip 5, and the top of the base B is likewise provided with a projecting tip 6. These projections may be made on one or both sides of the flange C, and the preformed section of filler will be made with longitudinal grooves 7 along opposite edges so that when the filler is forced into the space in the rail the tips 5 and 6 will engage the grooves 7 and interlock therewith, as shown in Figure 3. This idea may be applicable to a rail having the customary flanged head A¹. The section of filler is represented in all the figures as at 8.

The tips 5 and 6 are in reality continuous ribs and may be provided for at the time the rail is rolled, or else they may be brazed thereon, or in fact otherwise provided for so long as a projection is made which will engage the filler 8 when interlocked therewith.

I claim:

1. In combination, a rail, a filler therefor said filler being substantially continuous with the rail and comprising a preformed bituminous block-like member having the inherent quality of compressibility, and means for interlocking the filler with the rail, comprising means on the rail projecting into the space to be filled by the filler, said projection adapted to engage the filler and anchor the same to the rail.

2. In combination, a rail having a head, base and connecting web with a space between the head and base, and a filler for said space, said filler being substantially continuous with the rail and comprising a preformed bituminous block-like member hav-

- ing the inherent quality of compressibility and means on the rail engaging with the filler for anchoring the same in said space.
3. In combination, a rail having head, base and connecting web with a space between the head and base, and a filler for said space, said filler being substantially continuous with the rail and comprising a pre-formed bituminous block-like member having the inherent quality of compressibility, and means on the rail engaging with the filler for anchoring the same in said space, comprising a projection on the rail and a space in the filler made to receive and interlock with said projection.
4. In combination, a rail having a head, base and connecting web with a space between the head and base, and a filler for said space, said filler being substantially continuous with the rail and comprising a preformed bituminous block-like member having the inherent quality of compressibility, and means on the rail engaging with the filler for anchoring the same in said space, comprising a projection on the underside of the rail head, and a space in the top of the filler made to receive and interlock with said projection.
5. In combination, a rail having a head, base and connecting web with a space between the head and base, and a filler for said space, said filler being substantially continuous with the rail and comprising a preformed bituminous block-like member having the inherent quality of compressibility, and means on the rail engaging with the filler for anchoring the same in said space, comprising a projection on top of the rail base and a space in the base of the rail filler made to receive and interlock with said projection.
6. In combination, a rail having a head, base and connecting web with a space between the head and base, and a filler for said space, said filler being substantially continuous with the rail and comprising a pre-formed bituminous block-like member having the inherent quality of compressibility, and means on the rail engaging with the filler for anchoring the same in said space, comprising projections on the rail head and base, and spaces in the top and base of the filler made to receive and interlock with said projections.
7. A preformed rail filler of the class described, comprising preformed block-like compressible members having the inherent quality of compressibility and having means formed therein to receive and interlock with anchoring projections in the space of the rail to be filled thereby.
8. A preformed substantially soundproof rail filler comprising a preformed block-like compressible member of bituminous material mixed with roofing scrap, said member having the inherent quality of compressibility.
9. A preformed block-like strip composed of a mixture of bituminous material and roofing scrap, said strip being formed to fit between the head and base of a rail, and said strip being so formed as to be readily compressible.

Signed at Chicago, Illinois this 28th day of August 1926.

ALBERT C. FISCHER.
